(57) **CLAIM**

We claim the ornamental design for a refill cartridge for a film dispensing tool for stationery, as shown and described.

DESCRIPTION

FIG. 1 is a front view of the refill cartridge for a film dispensing tool for stationery showing our new design, the design having transparent sections as illustrated in FIG. 8;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a front perspective view thereof; and,

FIG. 8 is a front perspective view of the refill cartridge for a film dispensing tool of FIG. 1 showing transparent sections with shading.

The broken lines showing various features in the drawings are for illustrative purposes only and those features form no part of the claimed design.
